Fig. 3

Fig. 4

FIG. 1 is a perspective side view of a meat-chopper showing my new design;

FIG. 2 is a front view thereof;

FIG. 3 is a rear view thereof; and

FIG. 4 is a top view thereof.

The side view of this meat chopper not shown in the drawing has an appearance identical with the appearance of the perspective side view in FIG. 1 of the drawing.

I claim:

The ornamental design for a meat chopper, substantially as shown and described.
